UNITED STATES PATENT OFFICE.

CLAUDIO GARCIA HUELVES, OF SANTA CLARA, CUBA.

CAR OR WAGON.

Application filed October 25, 1924, Serial No. 745,869, and in Cuba August 28, 1924.

This invention relates to cars or wagons used for transporting materials, particularly the cane sugar from the cane fields to the mills, and its object is to provide a car or wagon which has a tilting platform associated to or in combination with the side gate; so that when the platform is raised up to be inclined on one of its sides, it automatically causes the gate to open, and reversely, when the platform is lowered to its horizontal or normal position, the gate is closed and also to provide an automatically actuated means for locking the gate in its closed position.

The invention is described with reference to the figures of the annexed drawings, in which:—

Fig. 1 is an elevation view of a car or wagon provided with the improvements forming the subject-matter of this invention, looking from the side of the gates.

Fig. 2 is a side elevation of the same car or wagon looking from the opposite side.

Fig. 3 is a cross-vertical section of the car or wagon on line 3—3 of Fig. 1, in the closed position of the car.

Fig. 4 is a view similar to that of Fig. 3, showing the open position of the car.

And Fig. 5 is an enlarged detail on line 5—5 of Fig. 3.

In the drawings, 1 designates a railroad car or wagon used for the transportation of the sugar cane in a particular manner, to which effect the car is divided in sections 2, preferably three in number, separated from each other by divisions 3. The bed or platform 4 of each section 2 is fixed to cross-bars 4' which are gyratorily mounted by means of end side plates 5' on a rocking shaft 5 mounted across the divisions 3 and along the car, at the same side where are located the discharge gates of the car, said rocking shaft 5 being supported on brackets 6 fixed on the lower corresponding side sill 7 of the car. The side of each section 2 opposite to the gate, is composed of a plurality of vertical stakes 8 separated from one another and higher than the wall 3 and connected together at their upper end by a longitudinal bar 9, each stake 8 being gyratorily articulated to platform 4 by means of two side plates 10 laterally fixed to the sides of each cross bar 4' and mounted on a short pivoting shaft 11 which passes through each stake 8, thus forming an individual pivotal connection for each stake 8.

This side wall in its normal position bears against the upper beam 12 of the corresponding side of each section 2 of the car. Each gate is composed of a plurality of 60 vertical stakes 13 connected at their lower end by means of a longitudinal plate 14 of double angle or Z section which has projecting downwards a hanging vertical flange 14', and each stake 13 is hinged to the upper beam 15 of the corresponding side of each section of the car by means of a supporting piece with individual hinge 16 united to said upper beam 15. Each gate is further re-inforced by means of a diagonal plate or 70 tie member 17 of angular section, which connects together the various stakes 13. The two movable side walls of each section 2 of the car are connected together by means of two upper slightly inclined bars 18 which 75 connect together the upper part of the first stake 8 and of the last stake 8 of a side wall with the upper beam 15 of the other side wall, the unions being articulated by means of pivoting pins 20 which respectively pass through the first and last stakes 8 and side plates 21 fixed to the inclined bars 18 and by means of pivoting pins 22 which pass through the same bars 18 and supporting plates 23 connected to beam 15. The gate 80 is also connected to the opposite side wall by means of two diagonal bars 24 which connect together the first and last stakes 8 of the closed side wall with the first and last stakes 13 of each gate, the articulated 85 unions being effected by means of pivoting pins 25 which pass through the stakes 8 and side plates 26 fixed to each bar 24 and by means of pivoting pins 27 which pass through the stakes 13 and through longitudinal slots 28' in side plates 28 fixed to each bar 24. Each upper longitudinal bar 9 has united to the ends and middle portions of its length supporting plates 29 forming eyes for connecting the hooks 30 100 hanging from the chains 31 forming part of any proper elevating mechanism which is not shown. Each diagonal bar 24 is of somewhat channelled shape in transverse section as indicated in Fig. 5, whose concave face frictions with the adjacent face of division 3 so as to offer no resistance to the friction of the canes and thus prevent said bars 24 from causing the retention of the same. Below each platform 4 a lever 105 is mounted on a supporting plate 32 laterally fixed to each cross tie-beam 35, said

lever having uneven arms 33 which terminates adjacent the closed wall in a projection or shoulder 34 bent at right angles to the portion 33 or extend vertically and upwardly directed in front of the lower side sill 7' of the car to butt against the lower face of the tilting platform 4, and said longer arm of the lever 33 passes through a slot 36 vertically formed in the web of the other lower side sill 7 of the car corresponding to the side of the gate, and terminates in a short projection or shoulder at 37 which slightly slopes outwards and frictionally engages the lower edge of outer face of the hanging vertical flange 14' of the side plate 14 fixed to the gate. Said lever 33 is provided with a weight 38 near the projection 37, whereby this lever tends normally to bear by its longer arm on the lower edge of the slot or opening 36 of the lower bolster 7 of the car.

The operation of the car is as follows: By operating any proper mechanism connected to the chains 31, the supporting plates 29 attached to the side wall formed by the stakes 8 are pulled up and at the same time the platform 4 tilts on the rocking shaft 5 owing to the articulation afforded by the pivoting pins 11 and the side wall formed by the stakes 8. At the same time that it ascends, the wall tends to withdraw into the interior of the car, owing to the fact that the tilting shaft 5 is fixedly located at the lower part of the opposite side. At the time that the tilting platform 4 starts to go up, the gate 13 does not yet open, outwardly, owing to the lost motion between the members 24 and gate 13, which is afforded by side plates 28 running on pins 27 along their longitudinal slots 28' at which end the gate 13 is gradually opened, and the cane is discharged without any obstruction through the open space of each gate 13 owing to the inclination of the platform 4 of the section. Owing to the weight 38, once the lever 33 has been freed from the pressure exerted upon the upwardly bent inner end 34 of the same by the platform 4, the projection 37 comes to its lower position, being freed from the lower flange 14' of plate 14 secured to stakes 13 before starting the opening movement of gate formed by stakes 13. After discharging the load of the car, the elevating mechanism of which the chains 31 form part is lowered whereby the platform 4 with the closed side wall 8 and the gate 13 comes down by their own weight and when the flange 14' of plate 14 engages the corresponding lower side sill 7, platform 2 follows its rocking motion on shaft 5, owing to lost motion between tie members 24 and stakes 13, until platform 4 butts against the end of the shoulder 34 and it presses the same downwards causing the lever 33 to pivot so as to raise up the

shoulder 37 of the other end for engaging the hanging flange 14', the gate being thus locked and prevented from opening, unless the side formed by the stakes 8 is raised up again.

It should be understood that the details of construction of the car can vary within the system of discharge of the same, without altering the essential feature of the invention, which is as set forth in the appended claims.

What I claim is:—

1. In cars or wagons, the combination of a tilting platform on one of its sides, a discharge side gate at the side of the car corresponding to the rocking shaft of the platform, a movable wall at the opposite side of the car and which is articulated to the platform, and connecting means between the movable wall and the gate, so that when the movable wall is raised with the platform the gate is automatically opened, and vice-versa.

2. In cars or wagons, the combination of a tilting platform on one of its sides, a discharge side gate at the side of the car corresponding to the rocking shaft of the platform, a movable wall at the opposite side of the car and which is articulated to the platform, and connecting means between the movable wall and the gate and the stationary frame of the car, so that when the movable wall is raised with the platform the gate is automatically opened and vice-versa.

3. In cars or wagons, the combination of a platform tilting on a rocking shaft at one of the sides of the car, a discharge side gate which is hinged at its upper edge on the same side of the car corresponding to the rocking shaft of the platform, a movable wall at the opposite side of the car which is articulated to the platform and is higher than the stationary frame of the car, articulated lost motion tie members which diagonally connect the movable wall to the gate, and articulated connection bars which connect the higher part of the movable wall to the part of the stationary frame of the car in which the gate is hinged, so that when the movable wall is raised with the platform by proper elevating means, the gate is automatically opened a few times afterward, and vice-versa.

4. In cars or wagons, the combination of a platform tilting on one of its sides, a discharge side gate which is hinged at its upper edge to the stationary frame of the car on the same side thereof corresponding to tilting center side of platform, and locking means of the gate which are mounted underneath the platform and in the stationary frame of the car, so that when the platform comes down to its normal position the gate is automatically locked after being in its closed position.

5. In cars or wagons, the combination of a platform tilting on one of its sides, a discharge side gate which is hinged at its upper edge to the stationary frame of the car, 5 on the same side thereof corresponding to tilting center side of platform and has at its lower free edge a vertical flange, and locking means of the gate which are mounted underneath the platform at 10 the stationary frame of the car and which are actuated to outwardly engage the vertical flange of the gate, so that when the platform comes down to its normal position the gate is automatically locked after being in 15 its closed position.

6. In cars or wagons, the combination of a platform tilting on one of its sides, a discharge side gate which is hinged at its upper edge to the stationary frame of the car 20 on the same side thereof corresponding to tilting center side of platform, and locking means of the gate which consist in a lever pivotally mounted on the stationary frame of the car underneath the platform and having one end passing outside the stationary 25 frame of the car, said lever having at its inner end an upwardly directed shoulder which act as a butt against the car platform and at its outer end said lever is provided 30 with a weight and another shoulder to engage the lower portion of the gate, so that

when the gate comes down to its normal position the gate is automatically locked after being in its closed position.

7. In cars or wagons, the combination of 35 a platform tilting on one of its sides, a discharge side gate which is hinged at its upper edge to the stationary frame of the car on the same side thereof corresponding to tilting center side of platform, and locking 40 means of the gate which consist in a lever of uneven arms which is pivotally mounted in transverse position to the stationary frame of the car underneath the platform and which has its longer arm provided with 45 a weight and extended through a slot or opening on the bolster of the car which is below the gate, said lever having at its inner end an upwardly directed shoulder which acts as a butt against the platform 50 of the car and at its outer end has another upwardly directed shoulder to engage the lower portion of the gate, so that when the platform comes down to its normal position, it may butt against the inner shoulder of 55 the lever and cause the same to rock on its pivot causing its outer shoulder to raise and engage the lower portion of the gate after the latter being in its closed position, and vice-versa.

In witness whereof I affix my signature.
CLAUDIO GARCIA HUELVES.
